UNITED STATES PATENT OFFICE.

GEORGE E. WILLERS, OF LAWRENCEBURG, INDIANA, ASSIGNOR TO A. D. COOK, INC., OF LAWRENCEBURG, INDIANA, A CORPORATION OF INDIANA.

DEEP-WELL-PUMP CONNECTING DEVICE.

Application filed July 16, 1925. Serial No. 44,027.

My invention relates to connecting devices adapted to connect upper and lower working barrels in deep well pumps.

It is the object of my invention to provide improvements for the deep well pump disclosed in my Patent No. 1,448,018, and, instead of providing an integral coupling with internal threads to retain an upper barrel, and with external threads to retain a lower barrel casing, with an extended internal spider for supporting an inner or lower working barrel, it is my object to provide for an upper bushing with internal threads adapted to support the upper barrel, and with external threads to support the lower working barrel casing, and to further provide a separable coupling member adapted to form a seat for a relief valve, with a spider formation adapted to admit liquid from the annular aperture between the lower working barrel casing and the lower working barrel into the upper barrel and to secure the lower working barrel to this coupling member. It is specifically my object to support this coupling member by exterior threads engaging threads on the inner side of the lower working barrel casing, which may conveniently be extensions of the interior threads of the lower working barrel casing by which the lower working barrel casing is supported from the bushing.

It is my purpose to provide with this novel construction for independent adjustable elements which permit longitudinal adjustment of the separable coupling within the lower working barrel casing so that the stroke of the lower plunger of a deep well pump may be regulated with regard to the relief valve with desired accuracy. I have a further object of so reinforcing the support for the lower barrel that there is no tendency for the supporting piece or spider to be broken off.

Referring to the drawing in which I have illustrated a preferred embodiment of my invention:

Figure 1 is a longitudinal vertical section of a deep well pump assembly.

Figure 2 is a horizontal section taken along the lines 2-2 in Figure 1.

Generally indicated at 1 is the upper barrel of the structure. A bushing 2 with its external threads recessed as at 3 supports the lower working barrel casing 4. The shaft

of the pump indicated at 5 carries the upper sucker piston 6 within the upper barrel and the lower piston 7 within the lower working barrel. A relief valve 8 through which the shaft extends is supported on a housing 9 which is wedged with a taper fit within the separable coupling member 10.

The separable coupling member is threaded throughout its outer periphery and the threads with which the lower barrel casing is supported by the bushing are extended as at 11 so that the separable coupling may be adjusted to a desired position within the lower barrel casing. Below the tapered portion of the separable coupling, internal threads 12 engage external threads of the lower working barrel 13, in which the piston 7 reciprocates. The separable coupling is provided with webs 14 and grooves 15 between the webs which admit the liquid from the lower working barrel through the annular aperture between the lower working barrel and the lower working barrel casing with the downstroke of the lower piston. The grooves discharge into the upper barrel through orifices or ports as indicated at 16 in the walls of the separable coupling.

The particularly useful results of my new structure as indicated in the foregoing statement of my objects, will be readily understood when it is considered that the bushing member, which in known structures has been usually extended forming an integral piece with the webbed portion and the portion forming the seat for the relief valve is in my new structure entirely independent. The separable coupling not only supports the lower working barrel much more rigidly, but by turning the separable coupling further down within the threads of the lower working barrel casing, any desired degree of clearance between the lower piston and the relief valve may be obtained.

Having thus described my invention, what I claim as new and desire to secure by Letters Patent, is:

1. In a deep well pump, an upper barrel, a lower barrel casing, a lower working barrel within the lower barrel casing, a housing between the upper barrel and the lower working barrel, a bushing for connecting the lower barrel casing with the upper barrel, and an independent member mounted within the lower barrel casing supporting the lower working barrel and the housing.

2. In a deep well pump, an upper barrel, a lower barrel casing, a lower working barrel within the lower barrel casing, a housing between the upper barrel and the lower working barrel, a bushing for supporting the lower barrel casing from the upper barrel, and adjustable means for retaining the lower working barrel and the housing independent of the bushing.
- 10 3. In a deep well pump, an upper barrel, a lower barrel casing, a lower working barrel

within the lower barrel casing, a housing between the upper barrel and the lower working barrel, a bushing for supporting the lower barrel casing from the upper barrel, and adjustable means for retaining the lower working barrel and the housing independent of the bushing, said means provided with recesses and ports and mounted in threads within the walls of the lower barrel 15 casing.

GEORGE E. WILLERS.
